UNITED STATES PATENT OFFICE.

WILLIAM F. COOPER, OF NORWALK, OHIO, ASSIGNOR TO THE A. B. CHASE COMPANY,
OF NORWALK, OHIO, A CORPORATION OF OHIO.

TRACKER-BOX FOR MECHANICAL MUSICAL INSTRUMENTS.

1,095,554.

Specification of Letters Patent.

Patented May 5, 1914.

Application filed July 18, 1906. Serial No. 326,642.

To all whom it may concern:

Be it known that I, WILLIAM F. COOPER, a citizen of the United States of America, residing at Norwalk, in the county of Huron 5 and State of Ohio, have invented certain new and useful Improvements in Tracker-Boxes for Mechanical Musical Instruments, of which the following is a specification, reference being had therein to the accompanying drawing.

This invention has relation to tracker boxes for mechanical musical instruments, and relates in particular to tracker boxes which are pivotally attached to a support 15 extending from the main portion of the apparatus.

The invention has for its object, the provision of novel means for supporting the tracker box in its elevated or active position in front of the key-board of the piano or other musical instrument to which the playing attachment is applied.

The invention has for its further object, the provision of novel means for shifting 25 the actuating mechanism of the tracker box, so as to cause the music roll and the take-up roll to be positively actuated alternately accordingly as the perforated sheet is being wound upon the take-up roll or upon the 30 music roll.

A further object of this invention is to provide a novel cover or casing for the actuating mechanism and the tracker box.

The invention has for its further object 35 the provision of novel means for making a connection between manually operable levers attached to a pivoted tracker-box, with a pneumatic action having operative devices to be actuated by said manually operated levers.

A still further object of the invention is to provide improvements in the general construction and arrangement of parts hereinafter described and claimed.

My improvements are illustrated in the accompanying drawings in the several figures of which like characters are employed to designate corresponding parts, and in which—

Figure 1 is a top plan view of part of a mechanical playing attachment for musical instruments including as a component part, my improved tracker box, shown conventionally. Fig. 2 is a perspective view of a 55 frame constituting a portion of the sta-

tionary support by which the tracker box is suspended from the other portion of the playing apparatus. Fig. 3 is a front elevation of one end of the tracker box, this view being on an enlarged scale and showing the mechanism for driving the music roll and the take-up roll. Fig. 4 is a perspective view of a movable frame by means of which the tracker box is pivotally attached to the stationary frame shown in Fig. 2. Fig. 5 is a vertical central sectional view of the tracker box. Fig. 6 is a fragmentary perspective view of a portion of the shifting devices of the tracker box. Fig. 7 is an end view of the tracker box with the end cap removed. Fig. 8 is a rear elevation of the same. Fig. 9 is a front elevation of one of the sprocket wheels of the operating mechanism of the tracker box. Fig. 10 is an edge view of the same wheel. Fig. 11 is a front elevation of another of the sprocket wheels of the operating mechanism of the tracker box. Fig. 12 is an edge view of the wheel shown in Fig. 10. Fig. 13 is a perspective view on an enlarged scale of the locking bolt by means of which the tracker box is located in its active position. Fig. 14 is a fragmentary perspective view on an enlarged scale of a portion of one of the expression levers. Fig. 15 is a fragmentary perspective view on an enlarged scale of a portion of the tempo lever. Fig. 16 is a perspective view of a removable cover or casing for the operating mechanism of the tracker box, and Fig. 17 is a perspective view of a locking bolt employed in connection with the cover or casing shown in Fig. 16. Fig. 18 is a cross sectional view of a portion of a piano showing the position of the point of pivotal connection of the tracker frame and its supporting frame, the tracker box being shown in its several positions.

Referring first to Fig. 1 of the drawing, which best shows the general arrangement 100 of parts and the position of the tracker box relatively to the remainder of the playing apparatus, 1 designates the main portion of the playing apparatus which, as it constitutes no part of my present invention, 105 need not be specifically described. This main portion of the apparatus is adapted to be placed within the case of the musical instrument which is to be mechanically operated, and it carries two horizontally disposed 110

supporting bars designated 2 which extend from the main portion 1 of the apparatus to a point without the case of the instrument, just below the key-bed thereof. The bars 5 2 are cut away on top at their outer ends and indented as shown at 3 to receive the cut-away and indented inner ends 4, 4 of the frame 5, the frame being provided with holes 6, which receive bolts which screw 10 into the bars 2, 2, and by means of which the frame is rigidly secured to the bars. The frame 5 is formed with depending lugs 7 which are pierced at 8 to receive bolts 9, by means of which the movable frame 15 of the tracker box is pivotally attached to the frame 5 as will be hereinafter more fully described. The frame 5 is also provided with laterally extending lugs 10, which are pierced as shown at 11, to receive thumb 20 screws which serve to steady the frame, these screws entering the bottom of the key-bed of the instrument to which the apparatus is attached. The frame 5 carries on its outer end pins 12, these pins having their ends 25 beveled and serving, as will be presently described and in connection with a spring actuated bolt, to sustain and lock the tracker box in its elevated or active position.

The tracker box proper is designated 13 30 and is supported upon a swinging frame 14 which is pivotally attached to the stationary frame 5 by the bolts 9, and is sustained in its elevated or active position by a spring-actuated rocking bolt 15 which has 35 a handle 16 at one end and which has bearings in lugs 17 formed on the upper surface of the frame 14. The bolt 15 which is separately shown in Fig. 13 carries two stirrups 18 which engage over the pins 12 when the 40 tracker box is raised and the bolt is caused to turn positively in one direction by means of a torsion spring 19, one end of this spring bearing against one of the lugs 17 on the frame 14 and the other end being 45 bent laterally and extended through the bolt 15 as shown in Fig. 13. Upon one end of the tracker box 13 a removable casing or 50 cover 20 is arranged, this cover inclosing the operating mechanism of the tracker box, and the other end of the tracker box carries a similar cover or casing 21, which latter, however, is without any function other than to render the contour of the tracker box regular and artistic in appearance.

The frame 14 is formed with hinged members 22 on its inner ends which are pierced for the passage of the bolts 9 by means of which this frame is pivotally attached to the frame 5, and the frame 14 is also formed 60 with a cross-bar 23, which cross-bar is provided with holes 26, 27, 28, that serve as bearings for rocking expression levers 29, 30 and 31. The cross-bar 23 is also formed with a hole 32 which serves as a bearing 65 for a rocking tempo and shifting lever 33.

A portion of the expression lever 29 is shown in Fig. 14 and this lever is connected to a rocking shaft 29' by hinge-joint 29'', the expression levers 30, 31 being respectively connected to rocking shafts 30', 31', by 70 hinge-joints 30'', 31''. All the hinge-joints 29'', 30'', 31'' are in substantial alinement with the bolts 9 which constitute the pivotal connection of the frame 14 with the frame 5 and the tempo lever 33 is connected to a 75 rocking shaft 33' by a universal joint connection which is disposed in alinement with the hinge-joints of the expression levers and their shafts. The universal joint connection of the tempo lever 33 with its rock-shaft 33' is shown in detail in Fig. 15 and is composed of an L-shaped member 33'' which is pivotally connected to the tempo lever 33 by a pivot 34 and is pivotally connected to the rock-shaft 33' by a pivot 35. 80

The forward end of the frame 14 has holes 26', 27', 28' and 32' which aline respectively with the holes 26, 27, 28, and 32, in the cross-bar 23, and the expression levers and tempo lever pass through the holes 90 in the front of the frame as well as through the holes in the cross-bar and are thus given a bearing at two points.

The frame 14 is formed with upwardly and forwardly projecting curved arms 35 which have inwardly projecting pierced lugs 36 that receive screws 37 by means of which the tracker bar 38 is attached to the arms 35. The outer casing of the tracker box proper incloses the arms 35 and the front portion of the frame 14 and such outer casing which is designated 13' is attached to the frame 14 by screws 13''. The tracker box has at each end a head which heads are designated respectively 39 and 40, and these 100 heads are secured by screws or other proper fastening devices to the curved arms 35. The head 40 at the right hand end of the tracker box carries the operating mechanism of the music roll and take-up roll, and the construction of this head and of the operating mechanism will be best understood by reference to Figs. 3, 6 and 7 of the drawing, to which I will now refer.

Upon the head 40 is mounted a frame 115 consisting of parallel plates 41, 42 connected by cross-braces 43, these plates being formed with alined bearings for the various shafts hereinafter described. A shaft 44 is mounted near the upper ends of the plates and this shaft carries a sprocket wheel 45 that is fixed on the shaft and a brake-wheel 46 also fixed on the shaft, a brake-shoe 47 carried by a spring-arm 48 bearing on this brake-wheel and serving to prevent the shaft 120 from turning too freely or from attaining an inordinately high speed, the spring 48 being attached to the cross-bar 43 by rivets 49 and the end of the spring which carries the shoe 47 being free. A second and lon- 125 130

itudinally slideable shaft 50 is journaled in the plates 41, 42, and this shaft carries a sprocket-wheel 51, which is loosely mounted on the shaft and is in vertical alinement 5 with the sprocket-wheel 45, a chain 52 passing over both sprocket-wheels 45 and 51 and serving to communicate motion from one to the other. The sprocket wheel 51 is loose on the shaft 50 and this shaft carries 10 another sprocket-wheel 53 which is fast on the shaft 50. The sprocket-wheel 51 carries a pin 55 which is adapted to enter a hole 56 formed in the sprocket-wheel 53 and the sprocket-wheel 53 carries a pin 57 which is 15 adapted to enter a hole 58 formed in the sprocket-wheel 51, these pins and holes constituting a clutch by means of which, at one position of the sprocket-wheel 53, it is clutched to the sprocket-wheel 51. A rocking lever 59 is journaled in a bracket 60 carried by the plate 42 and this lever has one end extending outwardly from the plate and then upwardly, said outwardly and upwardly extending end terminating in two 20 curved arms 61, 61, which embrace the sprocket-wheel 53, this lever 59 constituting the means by which the sprocket-wheel 53 and the shaft 50 are moved in either direction, so as to engage the wheel 53 with 25 or disengage it from the sprocket-wheel 51. Rocking motion is imparted to the rocking lever 59 by means of a longitudinally movable shipping rod 62 which passes through a hole in the depending arm 59' of the lever 35 59, and this shipping rod carries two adjustable stops 63 which are adapted to alternately contact with the depending end of the rod 59' of the rocking lever and rock the same in one direction or another ac- 40 cordingly as the sprocket-wheel 53 is to be engaged with or disengaged from the sprocket wheel 51. The shipping rod 62 is connected at its inner end to a depending arm 64 carried by the tempo lever 33 so that 45 as the tempo lever 33 is rocked in one direction or another, the shipping rod will be moved longitudinally in one direction or the other. A drive chain 65 passes over the sprocket-wheel 53 and this drive chain after 50 passing over the sprocket-wheel 53 extends horizontally and to the main portion 1 of the apparatus where it receives motion from motor mechanism constituting a portion of said main portion of the apparatus. In its 55 passage over the sprocket-wheel 53 to the main portion of the apparatus, the chain 65 passes over two guiding rollers 66 which are loosely mounted on stub shafts 67, carried by the head 40, and longitudinally movable 60 on said shaft. The shaft 44 extends through the plate 42 and through the head 40 and is formed with a notch 41' on its inner end that receives a lug 68 on the end of a stub shaft 69 carried by the music roll 70. The shaft 50 also extends through the 65 plate 42 and the head 40, and carries on its inner end a pinion 70', which, at one position of the shaft, meshes with a gear-wheel 71 fixed on a stub shaft 72 carried by the take-up roll 73 and at another position of the shaft 50 is thrown out of gear with said gear wheel 71. The casing 20 which incloses the above described mechanism mounted on the head 40, has its outer side closed and its inner side open, and said casing carries a vertically slideable locking bar 74 which is mounted in a slot 75 in the side of the casing, the lower end of the bar passing through a hole 75 in the bottom of the casing and being 80 bent at right angles as shown at 76 to provide a handle by means of which the bar may be moved longitudinally. The bar 74 is sustained and guided in the slot 75 by plates 76' and the said bar carries pins 77, 85 which engage the notches 78 in the plate 41 and serve to hold the casing in position, the inner edge of the open side of the casing fitting neatly around the outer edge of the head 40. 90

The parts being constructed and arranged in the manner hereinbefore described, operate in the following manner: In the active position of parts, the tracker box is in the position shown in Fig. 1, and a strip of perforated paper 79 carried by the music roll 70 has its free end attached to the take-up roll 73 and motion being communicated to the chain 65 from the mechanism of the main apparatus, and the pinion 70 being at 95 this time in mesh with the gear-wheel 71, motion will be communicated to the take-up roll and the paper wound from the music roll onto the take-up roll, passing over the tracker-bar 38, opening and closing the openings in the tracker bar in the usual manner, so as to permit the ingress of air and its passage through the tubes 80 to the main apparatus. When the paper has been unrolled from the music roll and all rolled up on 100 the take-up roll, the tempo lever 33 is rocked to the right and a longitudinal movement thereby imparted to the shipper rod 62, which in turn imparts a rocking motion to the lever 59, whereby the shaft 50 is moved 105 110 longitudinally and the pinion 70 thrown out of gear with the gear wheel 71. This movement of the shaft 50 also throws the sprocket-wheel 53 into mesh with the sprocket-wheel 51, whereby the sprocket-wheel 51 115 is rotated and motion imparted through the chain 52 to the sprocket-wheel 45, shaft 41 and the music roll. As the sprocket-wheel 51 is considerably larger than the sprocket-wheel 45, the shaft 41 will be given a much 120 faster movement than was imparted to the take-up roll, and consequently the music roll will revolve at a much more rapid rate than was given to the take-up roll whereby 125 the strip of paper will be rapidly rewound 130

upon the music roll. A reverse movement of the tempo lever will throw the pinion 70 into mesh with the gear-wheel 71 and will throw the sprocket-wheel 53 out of mesh 5 with the sprocket wheel 51 and restore the parts to the proper position for winding the strip of paper from the music roll onto the take-up roll. The tempo lever 33 has a considerable range of movement between 10 those portions of its movement which are required to move the shaft 50 longitudinally. The intermediate movement is utilized to operate the tempo mechanism of the main apparatus. The universal joint between the 15 tempo lever 33 and its rock shaft 33' permits of the tracker box being swung downwardly and inwardly at whatever position the tempo lever happens to occupy when the tracker box is swung downwardly and thus 20 obviates any danger of bending the tempo lever or its rock-shafts 33' if the tempo lever should happen to be left at either of its extreme positions when the tracker box is turned down.

25 To turn down the tracker box and swing it under the bars 2, it is only necessary to depress the handle 16 of the bolt 15, this movement releasing the stirrups 18 from engagement with the pins 12, this movement 30 giving a torsional twist to the spring 19. The tracker box is then lowered, and swung backwardly and under the bars 2 so as to be out of sight below the key-board of the instrument, in which position it may be 35 sustained by any ordinary spring-catch.

To restore the tracker box to its first position it is merely swung forward and raised until the frame 14 is in alinement with the frame 5, the stirrups 18 during the last portion 40 of the upward movement of the frame 14 bearing on the beveled ends of the pins 12 and rocking the bolt 15 against the tension of the spring 19 until the stirrups have slipped over the ends of the pins, and thereby 45 lock the tracker box in its elevated position.

If, at any time, it is desired to inspect the

mechanism carried by the plates 41, 42, the bar 74 is pulled downwardly so as to release the pins 77 from engagement with the plate 50 41, whereupon the cover 20 can be slipped off sidewise, thus affording ready access to the mechanism carried by said plates 41, 42. The throw of the tempo lever 33 between the 55 points where it actuates the lever 59 can be readily regulated by the adjustment of the stops 65.

I claim:

1. In a device of the character described, the combination with stationary supporting 60 means, a frame pivotally attached to said supporting means, pins carried by the stationary supporting means and a spring restrained bolt carried by the frame, said bolt having laterally-extending means for automatically engaging said pins during a movement of the frame in one direction.

2. In a device of the type described, the combination with stationary supporting means, and beveled pins carried by said stationary supporting means, of a frame pivotally attached to the supporting means, a rocking bolt carried by said frame, a spring connected to said bolt, and stirrups carried by said bolt and adapted to engage said 75 beveled pins.

3. The combination with a pivoted tracker box, a rocking tempo lever carried by said tracker box and a rocking shaft, said tempo lever and rocking shaft being connected by 80 a universal joint connection.

4. The combination with a tracker box having a head and driving mechanism carried by said head, of a casing inclosing said driving mechanism and a locking bar carried by said casing and adapted to engage a stationary portion of said mechanism.

In testimony whereof I affix my signature in the presence of two witnesses.

WILLIAM F. COOPER.
